UNITED STATES PATENT OFFICE.

EDWARD FRANCIS EVANS, OF PHOENIX, ARIZONA.

LADDER.

1,400,481.

Specification of Letters Patent. Patented Dec. 13, 1921.

Application filed November 1, 1920. Serial No. 421,042.

To all whom it may concern:

Be it known that I, EDWARD F. EVANS, a citizen of the United States, residing at Phoenix, in the county of Maricopa and 5 State of Arizona, have invented new and useful Improvements in Ladders, of which the following is a specification.

My present invention has reference to an improvement in ladder construction and may 10 be considered in the nature of an attachment whereby two ladder sections may be adjusted one on the other and effectively held in such adjusted position.

A further object is the production of a 15 device of this character in which shoe members carried by one ladder section are spring influenced into contacting engagement with the other ladder section, thus providing brake means between the sections for holding 20 one section adjusted on the other section.

A still further object is the production of 25 means for permitting longitudinal adjustment of one ladder section on another ladder section, in which means is provided for preventing the lateral movement of the section, certain of said means being carried by brake 30 shoes which are hingedly connected to one of the ladder sections and influenced by springs means on the said section for holding the same in frictional engagement with the second ladder section, whereby to permit of the adjustment of the last mentioned section on the first mentioned section in one direction and to hold the said last mentioned 35 section against movement on the first mentioned section in an opposite direction.

A still further object is the production of locking means in the nature of brake shoes carried by mechanism connected with one 40 ladder section for engaging with another ladder section to hold the last mentioned section against movement on the first mentioned section in one direction, means being also provided for swinging the shoes out of 45 engagement with the last mentioned ladder section to permit of the same being moved in either direction over the first mentioned section.

The foregoing objects, and others which 50 will appear as the nature of the invention is better understood, may be accomplished by a construction, combination and operative arrangement of parts, such as is disclosed by the drawings.

In the drawings:—

Figure 1 is a front elevation illustrating 55 the application of the improvement.

Fig. 2 is a side elevation thereof.

Fig. 3 is a rear elevation thereof.

Fig. 4 is a sectional view approximately on 60 the line 4—4 of Fig. 1.

Fig. 5 is a sectional view approximately on the line 5—5 of Fig. 2.

Fig. 6 is a sectional view approximately 65 on the line 6—6 of Fig. 2.

Both of the ladder members or sections employed in the construction illustrated, are of the usual construction, that is each comprises substantially rectangular stiles and rounds connecting the stiles. 70

As one of the ladder members or sections is to remain on the ground, the same will be referred to as the stationary section and is indicated by the numeral 1. The second section has its stiles contacting with the outer faces of the stiles of the fixed section, and being movable thereon will be referred to as the movable section. This section is indicated by the numeral 2. Fixed to the movable section 2, adjacent to the lower ends 75 thereof are plates 3 that have their outer ends inturned, as at 4, to contact with the inner edges of the stiles of the fixed ladder section 1, and the said inturned portions 4 are provided with inwardly extending lips 80 5 that engage with the inner faces of the said stiles of the fixed section.

On the inner faces of the stiles of the fixed section, preferably, but not necessarily, adjacent to the top thereof, there is secured 85 opposed bearing members 6. Through these members 6 there are passed the parallel end portions 7 of a substantially U-shaped yoke 8 that receives the ladder section 2. The portions 7 have inturned ends 9 to which is 90 pivotally connected the arched or curved rod 10. This rod 10, instead of being arched or curved, may be straight and may be centrally formed with a depending portion in the nature of a lip which is engaged by the 95 hooked end 11 of a bolt member 12. Swiveled, or otherwise connected to one of the rounds 13 of the fixed ladder section 1 is a substantially U-shaped member 14, the arms of which have threads at their outer ends. 100 On the arms of the member 14 there are spaced plates 15 and 16 respectively. The outer plates 15 contact with nuts 17 that are 105

secured on the outer ends of the said member 14. Both of the plates have central openings therethrough through which pass the bolt members. The end of the bolt member 12 is 5 engaged by a nut 18 that contacts with the inner plate, while surrounding the bolt and contacting with both of the plates is a helical spring 20. This mechanism provides means for normally swinging the yoke 8 in 10 one direction.

The numeral 22 indicates shoe members. Each shoe has its outer straight face centrally notched as at 22' and in these notches are received the outer straight or connecting 15 portion 21 for the arms of the substantially U-shaped yoke 8. Each of the shoes has its inner face provided with a compressible plate 23, and each of the shoes has its outer face formed with a flange or provided with 20 a plate 24 that contacts with the outer faces of the stiles of the slidable ladder section 2. The shoes 20 are of a width corresponding to the thickness of the stiles of the slidable ladder section 2, and the said shoes are held 25 against movement on the yoke in any desired or preferred manner, such for instance as by the contacting engagement of the said shoes with the side members or arms of the yoke. The outer straight member of the 30 yoke may be journaled in bearings in the shoes or may be received in recesses on the outer faces of the said shoes.

On the outer sides of the stiles of the fixed ladder section 1, are angle brackets 25, the 35 same being in the path of engagement with the side members of the yoke, and these brackets serve as means whereby one finger of the operator may engage with one of the brackets, the other finger on the same hand 40 of the operator may engage with one of the side members of the yoke, thus swinging the yoke to bring the shoes out of contact with the stiles of the ladder section 2. The other hand of the operator will grasp a round of 45 the ladder section 2, and move the same longitudinally over the ladder section 1, thus positioning the section 2 in proper position on the section 1. A release of pressure on

the yoke will permit of the spring means influencing the said yoke to cause the shoes to 50 be brought into frictional contact with the stiles of the movable ladder section 2. When so engaged the section 2 cannot be moved downwardly on the section 1, as the arms of the yoke are arranged at a downward angle, 55 and a pressure of the shoes thereagainst would only tend to force the said shoes into tighter frictional engagement with the stiles of the ladder section 2.

The improvement is extremely simple, 60 may be readily attached to ladders of the ordinary construction to convert the same into adjustable members, is strong and will positively prevent the accidental downward sliding of the movable ladder section on the 65 fixed ladder section.

Having thus described the invention, what I claim, is:—

A ladder comprising a fixed section and a movable section which contacts with and is 70 slidable on the fixed section, a yoke surrounding the sections and hingedly connected to the fixed section, a rod pivotally connected to the inner ends of the yoke, a bolt member having a hooked end engaging 75 the rod, a U-shaped element supported on one of the rounds of the fixed section, spaced plates on the arms of the U-shaped member, removable means for retaining the plates thereon, said bolt passing centrally 80 through both of the plates, a nut on the bolt contacting with the lower plate, a spring surrounding the bolt and contacting with both of the plates, shoes journaled on the outer member of the yoke, compressible 85 plates on the inner faces of the shoes and contacting with the outer faces of the stiles of the movable ladder section, flanges on the shoes contacting with the outer faces of the said stiles, angle brackets on the fixed 90 ladder section adjacent to the side arms of the yoke, and a fixed guide member on the movable section partly surrounding the stiles of the fixed section.

In testimony whereof I affix my signature. 95
EDWARD FRANCIS EVANS.
